UNITED STATES PATENT OFFICE.

SUTTON H. DRAPER, OF MISSOULA, MONTANA.

JOURNAL-BEARING BOX.

Application filed April 17, 1924. Serial No. 707,035.

This invention relates to journal-bearing boxes for locomotive and railway car axles. As such journal-bearing boxes have usually been constructed heretofore, there has not been adequate provision for adaptation to or compensation for the constantly varying position of the locomotive frame or truck frame with respect to the axle by the wheels of which the locomotive or car is supported upon the track. Although the axis of each axle changes its inclination as the locomotive or car passes about a curve and, to a slight extent, because of inequalities in the track, it may be considered, for the purposes of this application, that inclination of the axis of the axle remains unchanged and that the relative movement of the frame or body with respect to such axis is due to vertical movement or the side sway of the frame or body of the locomotive or car. Truly vertical movement of the body with respect to the axle is compensated for by provisions which permit relative vertical movement of the body, but side sway or tilting of the body is not adequately compensated for and as a consequence there is more or less tendency to a departure from parallelism as between the axis of the axle and the true axis of the bearing surface of the box, with consequent unequal distribution of load, unequal distribution of lubricant and therefore of wear, tendency to breakage due to unequal distribution of pressure, and heating. The present invention has for its object to provide a journal-bearing box which shall be capable of compensating for the variation in relative position of the body and axle and so shall overcome the difficulties mentioned. The invention will be more fully described herein-after with reference to the accompanying drawing in which it is illustrated and in which—

Figure 1 is a perspective view of a journal-bearing box constructed in accordance with the invention, the parts being shown as separated in order that the construction may be understood more readily.

Figure 2 is a view of the same in vertical section on a plane indicated by the broken line 2—2 of Figure 3.

Figure 3 is a view of the same in section on a horizontal plane indicated by the broken line 3—3 of Figure 2.

Figure 4 is a partial view, partly in elevation and partly in vertical section, illus-

trating the relation of an axle and journal-bearing box of the former construction.

Figure 5 is a similar view illustrating the relation of the axle and the improved journal-bearing box.

Referring first to Figure 4, which is intended to illustrate the tendencies in a journal-bearing box as heretofore constructed, in which the box 27, although it may be free for vertical movement in the jaws of the frame (which is not necessary to be shown), is nevertheless not free to tilt with respect to the frame, it will be seen that relative movement, in the nature of side sway, of the body and axle, as indicated by the lines *c d*, tends to bring about a displacement of the axle with respect to the box 27 so that the pressure between the axle and the box is at the point 30, on the upper side of the axle and against the bearing box at 32, and at the point 31, at the under side of the axle, with clearance, as indicated at 28 and 29. This condition brings about unequal distribution of the load and lubricant, with accumulation of the lubricant in the spaces 28 and 29 and grinding at the points 30 and 31. The bearing surfaces are not in uniform contact throughout their length and the load is therefore distributed unequally. Also, as will be noted the box, at its upper edge, bears hard against the hub plate 19, as at the point 32, while at the under side of the axle, as at 34, there is clearance. All of these conditions result in unequal wear, distortion, breakage, improper distribution of load and heating of bearings, and necessitates frequent renewals and refittings of hub plates and bearing brasses and excessive use of lubricant.

The improved construction is so designed as to overcome the difficulties above mentioned, the box 1, which receives the bearing brass 22 and the axle 20, being so supported as to permit such movement with respect to the frame or body of the locomotive or car that there shall be no tendency to relative displacement of the axle and box. As shown, the box 1 is formed with trunnions 7, the axis of which is at right angles to the axis of the axle. The trunnions are received in trunnion plates 6 which are free for vertical movement between the flanged faces 11 and 9 respectively of the wedge block 4 and the shoe 5. The wedge block 4 and the shoe 5 are also flanged vertically on their outer faces to receive the jaws of the frame mem-

ber. The relation between the jaws of the frame and the wedge block and shoe is substantially as usual and it is not necessary to show the frame member. The wedge block 5 4 may be set up from below to compensate for wear and to secure proper working relation of the several parts.

The upper surface of the box 1 is convexed on a radius of the axis of the trunnions 7, as shown at 14 in Figure 1, a bead 10 24, 25 being formed at the upper edges to retain lubricant and also to prevent displacement of the spring saddle block 2. The under side of the latter is concaved to fit 15 upon the convex bearing surface 14 of the box 1 and on its upper side is formed with seats 8 to receive the spring saddle 15 upon which rests the spring 16.

As illustrated in Figure 5, in the event 20 of any relative movement of the body and the axle 20, the spring saddle may move with the body as heretofore, but, by reason of the radius bearing between the spring saddle block 2 and the bearing or box 1, relative movement between the spring saddle, 25 and therefore the frame, on the one hand, and the bearing box on the other hand, will be permitted and there will be no tendency to loss of parallelism between the bearing 30 surfaces of the box 1 and the axle 20. Consequently the bearing surfaces will be in contact throughout their length, the load will be distributed uniformly, the lubricant will also be distributed uniformly, there 35 will be no pressure at one point or another and therefore no grinding between the contact surfaces of the axle and the bearing box, and at its outer end the bearing box will bear uniformly against the hub plate 40 19 of the wheel 18. It will be observed that if there is a relative displacement between the body and the axle, as indicated, for example, by the lines *c*, *d* of Figure 4 and *c'*, 45 *d'*, of Figure 5 the central transverse plane of the bearing box 1, with its bearing brass 22, will remain always at a right angle with respect to the axis of the axle, as indicated by the relations of the lines *a*, *a'* and *b*, *b'* to the lines *c'* and *d'* of Figure 5.

50 It will be understood that details of con-

struction will be varied to suit different conditions of use and that, except as pointed out in the claims, the invention is not restricted to the particular construction shown and described herein.

55

I claim as my invention:

1. A journal-bearing box for railway car and locomotive axles, comprising a bearing box to receive the axle, said box having trunnions at right angles to the axis of the axle, trunnion plates to receive the trunnions, means to support the trunnions with freedom for vertical movement and channeled plates to support the trunnion plates with freedom for vertical movement.

65

2. A journal-bearing box for railway car and locomotive axles comprising a bearing box to receive the axle, said box having trunnions at right angles to the axis of the axle, trunnion plates to receive the trunnions, means to support the trunnions with freedom for vertical movement and channeled plates to support the trunnion plates with freedom for vertical movement, one of said plates being wedge-shaped to take up looseness between the other parts.

70

3. A journal-bearing box for railway car and locomotive axles comprising a bearing box to receive the axle, means to support the box with freedom to turn on an axis at right angles to the axis of the axle, and a spring saddle supported by the bearing box, said box having a surface curved on the radius of said first mentioned axis to permit relative movement of the spring saddle with respect to the bearing box.

80

4. A journal-bearing box for railway car and locomotive axles comprising a bearing box to receive the axle, means to support the box with freedom to turn on an axis at right angles to the axis of the axle, and a spring saddle block on which the spring saddle is supported, said bearing box and said spring saddle block having bearing surfaces curved on the radius of said first mentioned axis to permit relative movement of the axle journal bearings.

90

This specification signed this 11th day of April, A. D. 1924.
